US00D956215S

(12) **United States Design Patent** (10) Patent No.: **US D956,215 S**
(45) Date of Patent: **** Jun. 28, 2022**

(54) **AUTOINJECTOR**

- (71) Applicant: **Janssen Pharmaceuticals, Inc.**, Titusville, NJ (US)
- (72) Inventors: **Peter Krulevitch**, San Antonio, TX (US); **Michael Cannamela**, Atlantic Highlands, NJ (US); **Yuji Ikeda**, New Providence, NJ (US); **Nick Foley**, Edinburgh (GB); **James McLusky**, Edinburgh (GB); **Jimmy Mower**, Edinburgh (GB); **Scott Martin**, Edinburgh (GB); **James Glencross**, Edinburgh (GB)
- (73) Assignee: **Janssen Pharmaceuticals, Inc.**, Titusville, NJ (US)
- (**) Term: **15 Years**
- (21) Appl. No.: **29/823,124**
- (22) Filed: **Jan. 14, 2022**

CLAIM

The ornamental design for an autoinjector, as shown and described.

DESCRIPTION

FIG. 1 is a front perspective view from above of an autoinjector showing our new design;

FIG. 2 is a rear perspective view from below of the autoinjector of FIG. 1;

FIG. 3 is a right side elevational view of FIG. 1, the left side elevational view corresponds;

FIG. 4 is a top plan view of FIG. 1;

FIG. 5 is a bottom plan view of FIG. 1,

FIG. 6 is a front elevational view of FIG. 1; and,

FIG. 7 is a rear elevational view of FIG. 1.

The portions shown in broken lines are unclaimed environment, and form no part of the claimed design.

1 Claim, 3 Drawing Sheets
